UNITED STATES PATENT OFFICE.

EDGAR A. MONFORT, OF NEW YORK, N. Y., ASSIGNOR, BY MESNE ASSIGNMENTS, TO THE UNIVERSAL ELECTRIC ARMS AND AMMUNITION COMPANY, OF SAME PLACE.

ELECTRICAL BREECH-LOADING FIRE-ARM.

SPECIFICATION forming part of Letters Patent No. 365,843, dated July 5, 1887.

Application filed November 18, 1882. Renewed March 28, 1885. Serial No. 160,531. (No model.) Patent'd in England January 9, 1883, No. 125; in France July 9, 1883, No. 156,553, and in Belgium July 9, 1883, No. 161,968.

To all whom it may concern:

Be it known that I, EDGAR A. MONFORT, a citizen of the United States, residing at New York, in the county and State of New York, have invented new and useful Improvements in Electrical Breech-Loading Fire-Arms, of which the following is a specification.

This invention relates to a breech-loading fire-arm in which an accumulator secondary battery or any suitable electric generator is located within the stock and the charge fired by means of an electric current derived from said battery and passed through a platinum wire which connects the terminals of the conducting-wires within the charge of powder on a cartridge with which the gun is loaded.

The object of my improvement is to insure connection between the wires in the cartridge and the poles of the battery when the gun is closed, and to such end I provide the breech-block with two non-corrodible metal contacts insulated from each other and disposed as hereinafter described.

A further object is to provide simple and effective means for making and breaking the circuit, whereby the gun can be fired by operating the circuit-breaker, which serves as a trigger, and by means of which the current is passed through the wires in the cartridge.

These objects I attain by means of the devices illustrated in the annexed drawings, in which—

Figure 1 is a longitudinal section through a breech-loading fire-arm provided with my improvements. Fig. 2 is a top or plan view of a portion of the same. Fig. 3 is an enlarged end view of the breech-block carrying the non-corrodible metal contacts. Fig. 4 represents a longitudinal section through the breech-block and its adjuncts. Fig. 5 shows an end view and a longitudinal section of the cartridge employed.

A indicates the stock of the gun, within the butt of which is arranged any suitable electric generator, B. One of the wires, b, from the battery passes forward through the stock of the gun to a metal plate, C, which is located in rear of the breech-block. The remaining

battery wire, b', connects with a spring plate, D, secured at one end within a recess in the under side of the stock. The free end of this spring is provided with a push-button, D', which works through an opening in a cap-plate secured to the stock, so as to cover the recess. This push-button, which projects from the under side of the stock, is located at the point where the trigger of a gun is usually found, so as to be conveniently manipulated by a person firing the gun. This spring, which serves as the circuit maker and breaker, will, when the push-button is pushed inwardly, be brought in contact with a metal plate, E, electrically connected with a bolt, F, which serves to connect said plate with the metal bed-plate G for the breech-block.

H indicates the breech-block, which, in the present instance, is hinged upon a pintle, h, so that it can be opened and swung to one side for loading. The breech-block can be provided with an extractor and be hinged upon the pintle, so that it can when open be pushed back, so as to cause the extractor to eject the cartridge. In such case the spring J, arranged upon the pintle, serves to throw the breech-block forward after the cartridge has been extracted. The breech-block is provided with a longitudinal bore, in which is located a pin, K, insulated from the breech-block by means of any suitable tube, L, of insulating material.

This pin, which is carried by the breech-block, projects rearwardly from the same, and when the breech-block is closed comes in contact with the metal plate C, which is insulated from the bed-plate F of the breech-block.

In the forward end of the breech-block are secured two platinum or other non-oxidizable metal contacts, one of which, M, is made in the form of a thin annular plate seated in the block around the tubular insulator L, while the other, N, is in the form of a thin disk fitted within such tube of insulating material and applied against the end of pin K.

The cartridge O, which constitutes the subject of a separate application, is provided with two longitudinal conductors, P P', which pass through a block, Q, of some insulating mate-

rial in the head of the cartridge, and have their terminals connected near the base of the shot or bullet, by means of a platinum wire, R. The outer ends of these conductors project slightly out from the outer face of block Q in the cartridge, one of said ends being located at the center of the block and the other eccentric to the center thereof. When the breech block is closed, the central wire, P, of the cartridge with which the gun is loaded will be in connection with one of the battery-wires through the plate C, pin K, and the contact N at the forward end of the pin, while the remaining wire, P', will be in connection with the breech-block through the outer annular contact, M.

If, now, the push-pin is pressed inwardly, so as to bring spring-plate D in contact with plate E, the wire P' will be in connection with the battery-wire b' through the said spring and plate, the bolt P, the breech-plate, the breech-block, and the contact M in the latter; but it will be obvious that this last-described arrangement of connections could be greatly modified without departing from my invention, and it will also be seen that my invention could be applied to a gun having a hinged tilting barrel, as well as to a gun having a fixed barrel and a hinged or sliding breech-block. By employing platinum or nickel contacts on the breech-block clean contacts will be preserved, and by arranging said contacts in the form of a disk insulated by a ring from an outer contact-ring, certainty of connection between the poles of the battery and the wires in the cartridge when the breech-block is closed or the barrel tilted down will be insured, since the disk will come in contact with the central wire of the cartridge, and the metal ring will be brought in contact with the remaining wire of the cartridge, although the

latter may be turned so as to bring the outer end of said wire above, below, or to either side of the central wire.

To fire the gun, the push-button is pressed inwardly, so as to operate the spring and close the circuit. The current passing through the platinum wire in the cartridge renders the said wire incandescent, and thereby causes the ignition of the powder. 45

What I claim is—

1. In a fire-arm in which the charge is ignited by an electrical current passing through a platinum wire connecting the terminals of two conductors which are passed into the powder within the cartridge, the two non-corrodible contacts insulated from each other and located in the forward end of the breech-block, said contacts being respectively in electrical connection with the poles of the battery, and also being adapted to connect the latter with the wires in the cartridge when the gun is loaded and closed ready for firing, substantially as described. 55

2. The combination, with the breech-block, 65 of the pin K, provided with a non-corrodible contact, N, and insulated from the breech-block through which it passes, the annular non-corrodible contact M, secured in the breech-block and insulated from the pin and 70 its contact, and metallic connections, substantially as described, between the poles of the battery and the said pin and breech-block, for the purpose specified.

In testimony whereof I have hereunto set 75 my hand in the presence of two subscribing witnesses.

EDGAR A. MONFORT.
